UNITED STATES PATENT OFFICE.

WILLIAM C. PEET, OF JERSEY CITY, NEW JERSEY, ASSIGNOR TO HOWARD & SCHERRIEBLE, OF PROVIDENCE, RHODE ISLAND.

DESIGN FOR LETTERS OR ALPHABET.

SPECIFICATION forming part of Design No. 13,677, dated February 27, 1883.

Application filed January 22, 1883. Term of patent 3½ years.

To all whom it may concern:

Be it known that I, WILLIAM C. PEET, a citizen of the United States, residing at Jersey City, county of Hudson, State of New Jersey, have invented and produced a new and original Design for Letters or Alphabet, of which the following is a specification, reference being had to the accompanying photographic illustrations, forming part thereof, in which all the letters of my newly designed alphabet are shown clearly.

The alphabet in its general appearance is suggestive of the characters employed in mediæval times in the so-called "illuminated" books of that period, but conforms more nearly to the form of modern type, so that the letters are more readily recognized by the general observer. The heavy straight strokes, as *a*, of the letters are provided with beads *b*, project-

ing from their sides, and with recesses *c* at their ends, while the heavy curved strokes *d* have recesses *e* at their sides and projecting beads *f* at their ends. The usual fine strokes crossing the ends of the heavy lines of the letters are replaced by volutes *i*. The *J* is distinguished from the *I* by a heavy double volute, *n*. The space within the letters is partially filled by fine lines *r*.

I claim—

The design for an alphabet, substantially as herein shown and described.

In testimony whereof I have signed my name to this specification in the presence of two subscribing witnesses.

WILLIAM C. PEET.

Witnesses:

C. F. McCALLOW,
C. H. MACHIN.
